UNITED STATES PATENT OFFICE.

MALCOLM CAMPBELL, OF BOSTON, MASSACHUSETTS.

ROTARY STEAM CLOTH-FINISHING PRESS.

SPECIFICATION forming part of Letters Patent No. 621,028, dated March 14, 1899.

Application filed October 3, 1894. Serial No. 524,814. (No model.)

To all whom it may concern:

Be it known that I, MALCOLM CAMPBELL, of Boston, in the county of Suffolk and State of Massachusetts, have invented certain new and useful Improvements in Rotary Steam Cloth-Finishing Presses, of which the following is a specification.

My invention relates to an improvement in rotary steam cloth-finishing presses, and has for its object, among other things, to provide means whereby the fabric may be pressed and finished without injuring the goods.

My invention consists in certain novel features of construction and arrangement of parts, which will be fully hereinafter described, and particularly pointed out in the claims.

Reference is to be had to the accompanying drawings, and the characters marked thereon, which form a part of this specification, like characters designating like parts or features, as the case may be, wherever they occur.

In the drawings, Figure 1 is an end view of a press embodying my invention. Fig. 1^a is a longitudinal section through the machine. Fig. 2 is an end view of a portion of the main apron. Fig. 3 is a top view of that part of the main apron shown in Fig. 2. Figs. 4 and 5 are details showing the manner of connecting the cloth, the paper apron, and the main apron and also the relation of the lugs in respect to the pressing-rolls. Figs. 6 and 7 are end and front views, respectively, of the pressing-rolls and their accessories. Fig. 8 shows a part of the means for adjusting the main cylinder and the star-wheels. Fig. 9 is a detail view showing the shaft *x*, its pinion *x*²¹, and a portion of the wheel *y*.

The framework of the machine *A*, the main cylinder *w*, the friction-rolls 10 and 12, the guide-rod *t*, rolls *n*, guide-rod *s*, brushes *l* and *l'*, friction-roll *S*, stretch-roll *S'*, steamers *j*³ and *k*³, winding-up rolls *c*³, or folder *i*³ may all be of the form and construction common in such machines. The main or large pressing-cylinder may be constructed of any material suitable for holding steam. The cylinder *w* and the steamers *j*³ and *k*³ may be connected with the steam-pipes in the usual way. These steamers *j*³ *k*³ are located at the top and the delivery side, respectively, of the machine, whereby the cloth is steamed before

it passes by the cylinder and also after it has passed the cylinder, but before it reaches the winding-up roll. The cloth passes first to the steamer *j*³ at the top of the machine, thence around said steamer by means of suitable rolls or rods to the stretching-roll *S'*, and thence to the cylinder. From the cylinder the cloth passes to the steamer *k*³ at the delivery side of the machine and from thence to the winding-roll. Upon these parts and the general structure of the machine I make no claim, my invention consisting in the novel means of pressing the fabric and in the novel means whereby the fabric is pressed and finished without injuring the goods, the fabric lying in a natural or normal condition, so far as stretching is concerned, while running through the press. In presses of this kind as heretofore constructed the fabric is subject to varying and frequently damaging strain owing to the varying speeds at which the several parts of such machines are driven. By my invention the stretching-roll, the main cylinder, the pressing-apron, the winding-up roll, and the fabric are arranged to move in unison, as are also the several rolls over which the fabric passes, all these parts being connected to and driven by the main shaft. The novel means for exerting pressure upon the fabric embodies a yielding feature that enables the press to exert a uniform pressure upon the goods and at the same time prevent injury to the fabric or press when places of union of two pieces of fabric or other inequality passes through the press. It is to be observed that the winding-up roll and stretch-roll are driven in unison.

Both ends of the machine being in duplicate, a description and illustration of the parts of one end will suffice for both.

Meshing with a spur-gear (not shown) upon the main shaft, on which the cylinder *w* is mounted, is a gear-wheel *y*, mounted upon a shaft *P*. This shaft is also provided with a pinion *Q*, rigidly mounted thereon. *Q'* and *R* represent two arms, each at one end being loosely mounted on a shaft *s'*. At the other end they are loosely mounted upon the shaft *P* and the shaft *T*, respectively. *s'* is a spur-gear meshing with the pinion *Q* and with a gear-wheel *T*², rigidly mounted upon the shaft *T'*. By this means provision is made for com-

municating power from the wheel y to the wheel T^2 when said wheel and its shaft T' are slid laterally, as will be hereinafter explained.

5 The shaft x , on which the main cylinder turns, is mounted at each end in a bearing E , constructed and arranged to slide vertically in ways E' in the frame of the machine to admit the raising and lowering of the shaft x and its cylinder. G is a rod provided at its ends with right and left hand screw-threads arranged to be screwed into the bosses F and H , respectively, the boss F being pivoted to the bearing E at F' and the boss H being integral with a strap H' . The strap H' fits about the eccentric I^2 , secured to the shaft I' , suitably mounted in the frame of the machine. Secured to the shaft I' is a spur-gear I , meshing with a pinion L on a shaft K , mounted 20 on the frame of the machine above the shaft I' . A hand-wheel J , secured to the shaft K , serves as a means to impart motion to the eccentric I^2 .

Star-wheels G' and G^2 are mounted upon 25 shafts h and T' , respectively, that are secured in bearings f , constructed and arranged to slide upon horizontal ways f' . The usual drums to support the apron are mounted on these shafts h and T' . d and d' represent right 30 and left hand screw-threads secured at one end in bosses c , pivoted by bolts e at nearly opposite points on the spur-gear I and at their other ends secured to bosses c' , pivoted by bolts e' to the sliding bearings $f f'$.

35 From the foregoing it will be seen that as the shaft I' is rotated the cylinder will be raised or lowered through the medium of the eccentric I^2 , while at the same time, through the medium of the rods $d d'$, the star-wheels $G' G^2$ will be moved away from or toward each other. By this means a constant tension is 40 kept upon the apron a , which passes over said star-wheels G' and G^2 and around said cylinder, as shown in the drawings. These 45 star-wheels are provided with teeth g to engage pins a^7 , projecting from the sides of the apron a , in order to impart motion to said apron. The teeth g on these wheels are faced in opposite directions. The teeth on the wheel G' , which is driven indirectly from the main 50 shaft, drives the apron, while the wheel G^2 derives its motion from the movement of the apron, the pins a^7 of which draw against the teeth of this wheel.

55 It may be found necessary to have a friction-band on the shaft of the star-wheel G^2 to keep the weight of the apron from running the apron out backward when the pressure is released. The apron a is composed of slats 60 a' , beveled at a^3 sufficiently to permit them to go over the wheels $G' G^2$ without the edges touching. These slats are secured at their ends by ears a^4 to links a^5 , pivoted together by the pins a^7 , thus forming an endless apron 65 that will readily conform to the cylinder w and to the wheels $G' G^2$. Inside these slats—that is, between the main apron and the cyl-

inder—is an apron of felt b and, if necessary, an apron of paper. These aprons are made endless by means of one of the slats a' being 70 so constructed that it will clamp and hold the ends of said felt or paper aprons. An end view of this construction is shown in Figs. 4 and 5. As here illustrated, one of the slats a' is made in two parts provided with perforated lugs a^8 , which register when the two parts are assembled and permit the two parts of the wheel between which the ends of the felt or paper apron have been placed to be securely clamped together by means of bolts 80 and nuts a^9 , thus also securing the ends of said felt apron and forming an endless apron of felt.

The clamping-lugs a^8 are placed at intervals across the slat to allow the slat to pass 85 the pressing-rolls o . (See Figs. 1 and 4.) The object of these pressing-rolls is to press the slats of the main apron firmly against the main-apron roll or cylinder w . These rolls are under the cylinder w and are held in place 90 in the main bed D of the machine by the shanks o^2 of the stands o' passing through said bed D . These rolls are made adjustable up and down by means of nuts and check-nuts r on the ends of said shanks. Springs 95 g are arranged on these shanks between the said bed D and the stands o' . By this means the rolls exert a yielding uniform pressure on the slats, permitting the slats and rolls to yield outwardly away from the cylinder in case of 100 an unevenness in the fabric or any other obstruction. These spring-rolls are located at suitable intervals across the bed D of the machine and spaced to permit the lugs a^8 to pass between them. (See Fig. 4.)

105 The wheel y meshes with a pinion x^{22} on the shaft $x x$. On this shaft is a band-wheel v , which drives a belt v' , which in turn drives the brushes $l l'$. The belt to drive the stretch-roll S' is driven from the star-wheel shaft T' , 110 said belt passing around the tension-pulley V , said tension-pulley being held in position by the lever T and weighted down by the weight u , so that as the drums on the shafts $T' h$ are thrown apart the belt will be kept at 115 the same tension at all times.

120 All the several parts of the press are so timed that they move in unison, so that all stretching of the material, which occurs in most of the rotary presses as at present constructed, wherein the cloth is dragged between the press-roll and one or more stationary beds, is prevented. The beds being held firm and the rolls rotating causes the fabric to stretch out of shape and also elongate to quite an extent, 125 according to the amount of pressure and friction brought to bear on it. By my invention all stretching is avoided, since the fabric, the apron, the stretch-roll, the winding-up roll, and the cylinder all move in unison. The fabric R passes into the press, as indicated by the darts in Fig. 1, passing over the friction-roll l^0 , down through the guide-rod t and the roll n and the guide-rods s , one side being

brushed by the brush *l* and the other by the brush *l'*. The fabric then passes around the friction-roll *l²* and over the drum on the shaft *h* to the steamer *j*³, passing over the stretching-roll *S'*, and then to the main cylinder *w*. Passing between said cylinder and apron the fabric is delivered from the main apron to the steamer *h³* and thence to the wind-up roll *c³* or folder *i³*.

10 The pressure upon the fabric between the cylinder *w* and the main apron is regulated by raising or lowering the said cylinder by the means already hereinbefore described.

15 *k¹⁰* and *l¹⁰* are band-wheels mounted upon the shaft *j*. The wheel *k¹⁰* receives the belt that drives the winding-up roll, while a short belt *w³* on the wheel *l¹⁰* communicates motion to the stretching-roll *S'*.

20 Having thus explained the nature of my invention and described a way of constructing and using the same, though without attempting to set forth all of the forms in which it may be made or all of the modes of its use, what I claim, and desire to secure by Letters Patent, 25 is—

1. In a rotary steam-press, in combination, a main cylinder, an endless apron surrounding a portion of the periphery of said cylinder, a series of rows of presser-rolls arranged 30 below said apron, each of said rows being composed of two or more individual rolls yieldingly mounted in the bed of the machine, whereby uniform pressure is exerted upon said apron throughout its entire width, substantially as and for the purpose set forth.

35 2. In a rotary steam-press, in combination, a vertically-adjustable main cylinder, horizontally-adjustable star-wheels, a main apron, yieldingly-mounted pressing-rolls and means 40 for adjusting said cylinder and star-wheels at a single operation, substantially as and for the purpose described.

45 3. In a rotary steam-press, in combination, a vertically-adjustable main cylinder, horizontally-adjustable star-wheels, a main apron surrounding a portion of the periphery of said cylinder and provided with laterally-extending pins arranged to be engaged by said star-wheels, means for adjusting said cylinder, and connections between said cylinder and star-wheels whereby a uniform tension is maintained upon the said apron in all adjustments of said cylinder, substantially as and for the purpose set forth.

50 4. In a rotary steam-press, in combination, a main cylinder, an endless apron surrounding a portion of the periphery of said cylinder, and a series of rows of pressing-rolls mounted in the bed of the machine with the 55 said apron between the said rolls and said cylinder, each of said rows being composed of two or more separate rolls mounted in stands, said stands having shanks passing

through the bed of the machine and provided with nuts at their ends and springs arranged 65 on said shanks between the bed of the machine and some projecting part of said stands, substantially as and for the purpose set forth.

5 In a rotary steam-press, in combination, a main cylinder, pressing-rolls, a main apron 70 surrounding a portion of said cylinder and arranged between said cylinder and rolls, horizontally-adjustable star-wheels *G'G²*, the gear-wheel *I* mounted on the shaft *I'*, the arms *d d'* connecting said wheel *I* with said star-wheels, 75 the eccentric *I²* on the shaft *I*, the strap *H*, rod *G*, and means for imparting motion to said shaft *I'* and gear-wheel *I*, whereby the said cylinder and star-wheels may be adjusted at one operation, substantially as and for the 80 purpose described.

6 In a rotary steam-press, in combination, a main apron comprising in its construction a series of slats segmental in cross-section, one of said slats being made in two parts, 85 corresponding lugs upon each of said parts, detachable means for uniting said lugs and gripping the said two parts of said slat together, and an inner apron having its ends arranged between and held by the edges of 90 the said two-part slat, substantially as and for the purpose set forth.

7 In a rotary steam-press, in combination, a main cylinder; a main apron comprising in its construction a series of slats segmental in 95 cross-section, one of said slats being made in two parts, corresponding lugs upon each of said parts, means for uniting said lugs and gripping the said two parts of said slats together; a row of pressing-rolls mounted in 100 the bed of the machine with said apron between said rolls and said cylinder, said row being composed of two or more separate rolls spaced apart to permit said lugs to pass between them.

105 8. In a rotary steam-press, in combination, an adjustable main cylinder, adjustable star-wheels, a main apron surrounding a portion of the periphery of said cylinder and mounted upon and carried by said star-wheels, means 110 for adjusting said cylinder, and connections between said star-wheels and said cylinder whereby said parts can be adjusted at one operation and uniform tension may be maintained upon the apron in all adjustments of 115 said cylinder, substantially as and for the purpose set forth.

120 In testimony whereof I have signed my name to this specification, in the presence of two subscribing witnesses, this 1st day of October, A. D. 1894.

MALCOLM CAMPBELL.

Witnesses:
